UNITED STATES PATENT OFFICE.

REINHARD E. BARTELS, OF LYNN, MASSACHUSETTS.

APPARATUS FOR LOCATING SHANK STIFFENERS ON SHANK PIECES FOR TURN SHOES.

Original application filed April 26, 1920, Serial No. 376,633. Divided and this application filed May 17, 1922. Serial No. 561,593.

To all whom it may concern:

Be it known that I, REINHARD E. BARTELS, a citizen of the United States, residing at Lynn, in the county of Essex and State of Massachusetts, have invented new and useful Improvements in Apparatus for Locating Shank Stiffeners on Shank Pieces for Turn Shoes, of which the following is a specification.

10 In assembling rigid shank stiffeners in shoes, the forward end of the shank stiffener should be located a short distance back of or "below" the break line of the sole in order that the resiliency of the shoe at the break line may not be impaired and the shoe thereby ruined.

The shank stiffener is attached to the shank of the sole or in turn shoes to a shank piece having a heel and shank but no fore-part, while the sole or shank piece is flat and before it has been shaped to its final form, and for this reason it is difficult to judge when locating the stiffener, where the break line will be on the sole or shank piece when the shoe is completed. Consequently, many soles have been spoiled by the location of the shank stiffener too far forward or too far back relative to the break line, in the first instance, destroying the resiliency of the sole at the break line, and in the second, throwing off the tread of the heel, either of which faults is undesirable from the standpoint of good workmanship, if not fatal to the usefulness of the shoe.

25 The break line on the turn shoe shank has no definite location and is arbitrarily determined by the manufacturer. That is, in placing the shank in the shoe, the manufacturer may extend the forward end of the shank as far forward of the break line of the shoe as his fancy or judgment may dictate. In view of the arbitrary location of the break line as set forth above, the position of the forward end of the shank stiffener on the shank may be determined by measuring rearwardly from the forward end of the shank a distance equal to the distance of the break line therefrom plus the distance that the forward end of the stiffener is to be positioned back of the break line.

30 One object of my invention is to produce a gaging apparatus whereby the workman can quickly and accurately locate the stiffener on the shank piece for any given style and size of shoe.

Another object of my invention is to provide means whereby when the desired point for the end of the shank stiffener on a shank piece of one size of a certain style has been located, the corresponding point for any other size of that same style may be readily located.

35 A still further object is to produce mechanical means whereby the desired point in any given shank piece may be readily and accurately located.

40 A specific embodiment of my invention by which the above objects may be accomplished is illustrated on the accompanying drawings, this application being a division 70 of application Serial Number 376,633 filed April 26, 1920, for apparatus for locating shank stiffeners in shoe soles.

45 Referring to these drawings,

Figure 1 is a plan of the apparatus showing a shank stiffener in place thereon and the shank in dotted lines.

50 Figure 2 is a longitudinal section on line 2—2 of Figure 1.

55 Figure 3 is a section on line 3—3 of Figure 2.

60 Figure 4 is a plan of the shank with the stiffener attached thereto.

65 Figure 5 is a side elevation showing the shank and stiffener molded to form for use 85 in a shoe.

70 Figure 6 is a side elevation of a shank stiffener.

75 In the case of a turn shoe, while the shank piece is in the form of a flat blank, the stiffener is preferably formed prior to attachment thereof to the shank, with a longitudinal ridge extending to within a short distance of the ends thereof. A form of stiffener to be used with a turn shoe shank 90 is illustrated at 42 in Figure 6, the longitudinal ridge being indicated by the reference numeral 43 and the securing tines by the numeral 44. It will be noted that these tines extend from the opposite side 100 of the shank stiffener from that on which the ridge is located.

80 Referring to Figures 1, 2, and 3, 50 indicates a plate provided with means for holding the shank stiffener in fixed position 105 thereon. This means comprises a support for the shank stiffener preferably formed by cutting a slot 51 longitudinally through the plate and covering said slot with a thin sheet of metal 52, as brass, aluminum, or the like, 110

formed with a longitudinal depression 53 therein. The purpose of this depression is to receive the ridge of the shank stiffener when said stiffener is placed on the plate, as 5 will hereinafter be set forth. Bordering the slot 51 on three sides is a U-shaped brace member 54, which serves to hold the sheet of metal in place and prevents lateral displacement of the shank stiffener, when 10 placed on the plate. This brace member may be formed integral with the plate but is preferably made separately and attached thereto in some suitable manner as by a screw or the like, (see Figure 1 of the drawings). 15

Located a short distance in front of the brace member 53 is an abutment member 55 against which the forward end of the shank stiffener abuts when placed between the arms 20 of the U-shaped brace member in position to be attached to the shank. The U-shaped member 54 may be made longitudinally adjustable to adapt it to confine the shank stiffener in its position abutting against the member 55 if so desired. For this purpose 25 the plate 50 is shown in Figure 2 as provided with a plurality of threaded openings in any of which a screw 500 for fixing the member 54 thereto may be passed.

30 The plate is also provided with suitable guide members for positioning the shank in proper relation above the shank stiffener to be attached thereto. There may be any suitable number of these guide members, three 35 being shown in Figure 1, comprising an end guide member 56 in front of abutment 55, and two side guides 57 and 58. The guide members are L-shaped, having long arms which lie against the plate, and short abutment arms 56^a, 57^a, and 58^a which project 40 upwardly therefrom forming abutments against which the shank is placed in positioning it above the shank stiffener. The 45 guides are provided with suitable means whereby they may be adjusted to a shank of any dimensions and to position the same with its longitudinal median line directly above that of the stiffener. As shown in Figure 1, this means comprises slots 45 in 50 the long arms of the guides and set screws 46 located in said slot and screwed into the plate.

With shanks to be treated alike, the 55 operation is as follows: The distance on the shank relative to the break line, as indicated above is determined and measured forwardly on the plate from the rear of the abutment member 55 and abutment arms 56^a placed at this point, and the side guide members 57 and 58 are set so as to position the shank above the shank stiffener in order that 60 the longitudinal center lines of both of these members will coincide. When the device is so set, a shank stiffener is slipped into place 65 with the tines extending upward and a

shank is placed thereabove abutting the brace members in the manner, as set forth above, and is struck with a hammer at a point above where the tines are located.

In practice, it is desirable in this operation to attach the shank support to a turn shoe shank only at the forward end and securely enough for the two members to remain attached in proper position relative to each other until the shank, which at this 75 stage is in the form of a flat blank, can be molded into a suitable shape to be placed in a shoe. The shank stiffener is fastened securely in place in the molding of the shank to form. Under some circumstances, however, it is desirable to attach the shank stiffener to the shank at both ends in the initial operation and by a single operation of the machine.

In order to facilitate the setting of the 85 end guide member to suit various sizes and styles of shoe, plate 50 may be provided with longitudinal graduations corresponding to the various lengths of shank piece for any given size, a cooperating reference 90 line being made on the guide member 56 for each style requiring a different setting of the guide member. By bringing the style mark in registry with the size mark for the size desired, the guide 56 is correctly 95 positioned for locating the stiffener on the shank for that size and style. Graduations for the side guides 57 and 58 are not important since it is an easy matter to set them so as to position the stiffener in the longitudinal center of the shank.

Having thus described an embodiment of this invention it should be evident that many changes and modifications might be made therein without departing from its 105 spirit and scope.

I claim:

1. A device for locating a shank stiffener in a desired position on a shank, comprising a support, means on the support for holding the shank stiffener definitely positioned on the support, and abutments on the support against which the shank may be placed so as to position the shank above the shank stiffener in position to be attached thereto in the desired position.

2. A device for positioning a shank and shank stiffener relatively to each other, so that the shank stiffener may be attached to the shank in a desired position thereon, comprising a plate having means thereon for holding the shank stiffener in a fixed position, and abutment members on said plate adapted to be adjusted to position a shank above said shank stiffener in the desired 115 position relative thereto.

3. A device for positioning a shank member and shank stiffener member relatively to each other, so that the shank stiffener may be attached to the shank in a desired 130

position thereon, comprising a plate having means thereon for holding one of said members in a fixed position, and abutments on said plate adapted to be adjusted to position the other of said members above said fixed member in the desired position relative thereto.

4. A device for locating a stiffener on a shank piece, which comprises a plate having means carried thereby for positioning the shank stiffener, and means for correctly positioning a shank piece on said plate relative to said stiffener.

5. A device for locating a stiffener on a shank piece, which comprises a plate hav-

ing means for positioning a shank stiffener, and means adjustable on said plate to correctly place a shank piece over said stiffener.

6. A device for locating a stiffener on a shank piece, which comprises a plate having means for positioning a shank stiffener, means adjustable on said plate to correctly place a shank piece relative to said stiffener, and means for indicating the adjustment of said adjustable means for different sizes and styles of shoes.

In testimony whereof I have affixed my signature.

REINHARD E. BARTELS.
